UNITED STATES PATENT OFFICE.

BERTUS A. LAKE, OF BIG PRAIRIE, OHIO.

SADIRON.

Application filed July 5, 1928. Serial No. 290,303.

The invention relates to self-heating sad irons and more particularly to a two piece body construction for the iron.

The object of the improvement is to provide an iron comprising a base and a separable side wall portion to which is connected a removable top or cover portion, the construction being such that a circulation of air is assured through the hollow interior of the iron to provide sufficient oxygen for combustion, the air passing between the base and the underside of the side wall portion and out of the hollow body between the cover and the upper edge portion of the side walls.

The above and other objects may be attained by constructing the improved sad iron in the manner illustrated in the accompanying drawings, in which

20 Figure 1 is a side elevation of the iron embodying the invention;

Fig. 2, a plan sectional view taken substantially on the line 2—2, Fig. 1, the burner being removed;

25 Fig. 3, a longitudinal sectional view through the improved iron;

Fig. 4, a transverse sectional view taken substantially on the line 4—4, Fig. 2; and

30 Fig. 5, a similar section taken substantially on the line 5—5, Fig. 2.

Similar numerals refer to similar parts throughout the several views.

The body of the improved iron may comprise the base 1, which is provided, spaced from its edge, with the upright flange 2 extending substantially entirely around the upper surface thereof.

35 Bosses 3 may be formed integral with the flange 2 at transversely opposite points, intermediate the ends of the base, said bosses being provided with the tapped bores 4.

The toe and heel portions of the base may be of greater height than the intervening portions as indicated at 5 and 6.

45 The intermediate or side wall portion of the body is indicated generally at 7 and comprises a hollow shell, open at its upper and lower ends and having a contour substantially conforming to that of the base.

50 This side wall is undercut at its toe and heel portions as shown at 8 and 9, respectively, to rest upon the high portions 5 and 6 of the base. The intermediate portions thereof being spaced above the base throughout the greater portion of the length of the iron, forming elongated openings or slots

10 between the lower edges of the side walls and the upper surface of the base.

The toe end of the side wall portion of the body may be inclined forward and downward as shown and provided with the extension 11 at its upper end.

A similar extension, preferably of less height may be provided at the heel end of the side wall portion as indicated at 12.

The upper edge of the side wall intermediate the heel and toe is of considerably less height and may be provided with notches as shown at 13.

55 A horizontal flange 14 may extend inward from each side of the side wall member at a point near its upper edge. These flanges are spaced above the lugs 3 of the base and provided with apertures 15 adapted to be registered with the tapped bores 4 of the base, the attaching screws 16 being located through the apertures of the flanges and engaged in said tapped bores of the lugs to secure the side wall portion of the body upon the base, and provided for quickly and easily removing the same therefrom.

60 The cover for the body may be formed of two parts comprising the upper plate 17 and the under plate 18 provided upon its upper surface with the spacing lugs 19, air spaces 20 being formed between the upper and lower plates to permit cooling air to circulate therethrough, in order to prevent overheating of the cover.

65 The forward end of the top plate 17 of the cover is adapted to rest upon the extension 11 at the toe end of the side wall portion and the inclined forward end 21 of the lower plate 18 of the cover is adapted to frictionally engage the inclined inner surface 22 of the side wall portion.

70 The rear end portion of the lower plate 18 is arranged to rest upon the extension 12 at the heel end of the side wall portion and a depending lug 23 upon the lower plate is adapted to be engaged by the set screw 24 located through the heel end of the side wall member forcing the cover into position and holding the same securely upon the top of the side wall.

75 A handle bracket 25 may be connected to the cover as by the screws 26 which secure the upper and lower plates 17 and 18 together. The handle grip 27, which may be formed of wood or the like, is carried by this handle bracket.

80 The burner 28, which is located within the

hollow interior of the iron body may be of any desired construction preferably U-shaped as shown, the rear lower end portion thereof being adapted to be spaced from the base by means of the transverse rib or lug 29 formed upon the base.

The generator tube 30 may be connected to the burner in usual manner and communicates with the lower end of the fuel tank 10 31 through a valve 32. When the burner is lighted it will be seen that a circulation of air through the hollow body of the iron will be maintained, providing sufficient oxygen for combustion.

15 Air will enter the body through the slots 10, between the side wall member and the base and will pass upward between the side walls and the ribs 2 and then into the interior of the body, the burned gases passing 20 out through the openings between the upper edges of the side walls and the cover.

By forming the cover of two plates spaced apart by ribs or the like a circulation of cooling air through the spaces 20 between 25 the upper and lower plates will prevent the upper plate from overheating and thus prevent the handle bracket from becoming uncomfortably hot.

I claim:

1. A sad iron including a hollow body 30 comprising a base having an upright flange spaced from its edge, a side wall portion spaced from said upright flange and having horizontal flanges upon its interior, screws located through said horizontal flanges and 35 upright flange to connect the side wall and base together, a burner within the hollow body and a cover detachably connected to the upper portion of the side wall.

2. A sad iron including a hollow body 40 comprising a base having an upright flange spaced from its edge, a side wall portion spaced from said upright flange and having horizontal flanges upon its interior, screws located through said horizontal flanges and 45 upright flange to connect the side wall and base together, a burner within the hollow body and a cover detachably connected to the upper portion of the side wall, the body being provided with openings at the lower 50 and upper edges of the side wall to permit a circulation of air through the interior of the hollow body.

In testimony that I claim the above, I have hereunto subscribed my name.

BERTUS A. LAKE.
